CLAIM

The ornamental design for a headband as shown and described.

DESCRIPTION

FIG. 1 is a perspective view of a first embodiment of a headband;

FIG. 2 is a left-side view thereof;

FIG. 3 is a right-side view thereof;

FIG. 4 is a front view thereof;

FIG. 5 is a rear view thereof;

FIG. 6 is a top view thereof; and

FIG. 7 is a bottom view thereof.

FIG. 8 is a perspective view of a second embodiment of a headband;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines illustrate wire frame lines, on the upper and side portions of the headband, that form no part of the claimed design; the broken lines illustrate wire frame lines on the side, head, ear, and microphone modules that form no part of the claimed design. All broken lines form no part of the claimed design.
